METHOD FOR FORMING ZINC SHEETS

Clinton I. Wasson, Muncie, Ind.

Application April 28, 1937, Serial No. 139,381

2 Claims. (Cl. 29—148)

This invention relates to a process for preparing and forming zinc in sheets in a continuous operation from the molten zinc to the finished sheet thickness.

As indicated, the primary object of the invention is to provide a method which may be continuous in operation rather than following the heretofore practice of molding billets and then passing these billets back and forth between rolls.

10 A further feature of the invention is the maintaining of the correct temperatures in the zinc before and after being reduced in thickness.

These and other objects of the invention will become apparent to those skilled in the art in the 15 following description of the invention which is illustrated more or less diagrammatically in the accompanying drawing, in which

Fig. 1 is a vertical longitudinal section through apparatus used in performing the invention;

20 Fig. 2, a detail in transverse section on the line 2—2 in Fig. 1; and

Fig. 3, a similar detail of a modified form.

Like characters of reference indicate like parts in the two views in the drawing.

25 I provide a quantity of molten zinc 10 in any suitable tank 11, from which the zinc may be drawn at will such as by lifting a gate 12 by a handle 13 to permit the zinc to flow out a spout 14.

A drum 15 is revolubly mounted by means of a 30 center shaft 16 whereby the drum 15 may be revolved by any suitable means (not here shown).

Back of the drum 15 is positioned a fixed plate 17 having a curvature, the radius of which slightly exceeds that of the outer face of the drum 15.

35 The plate 17 is spaced from the face of the drum 15 a distance which determines the thickness of the sheet of zinc before it reaches the initial set of rolls as will be further described. The plate 17 is preferably provided with a cooling chamber 18 immediately therebehind.

The discharge end of the spout 14 is positioned to cause the molten zinc 10 to flow into a hopper 19, the underside of which discharges into a space between the plate 17 and the periphery of the

40 drum 15. The zinc 10 is flowed into the hopper 19 to maintain a sufficient head on the molten zinc as will carry the zinc into the forming space between the drum 15 and plate 17.

The drum 15 is continuously revolved in the 45 direction of the down flowing zinc, counter-clockwise in the particular instance, so that as the molten zinc strikes the drum 15 and solidifies between it and the plate 17, the zinc then becomes a sheet which is carried on down around under the drum 15 to be stripped therefrom by a stripper

20 so as to direct the sheet 21 on to a table 22. A seal is provided at each end of the drum between it and the plate 17 so as to define the width of the sheet 21. In the particular form herein shown, Fig. 2, the drum is provided with an annular flange at each end extending from the drum to the plate 17 sufficiently close so as to prevent leakage of the zinc when it first drops into the space between the drum and the plate.

In order to insure movement of the sheet 21 in 10 the space between the drum and plate, the drum may be provided with one or more roughened areas such as is indicated by the teeth 23, Fig. 2. These teeth receive the molten zinc therearound so that when the zinc solidifies, the sheet is then gripped firmly by the drum to insure travel of the sheet therewith. The drum 15 is preferably hollow so that a cooling fluid such as water may be introduced through the shaft 16 for the purpose of cooling the zinc contacting face of the drum as may be required. Likewise the chamber 18 may receive a cooling fluid to circulate therethrough for the purpose of controlling the temperature of the plate 17 and solidifying the zinc as desired.

The sheet of zinc 21 is carried across the table 22 to pass between the customary set of rolls 24, 25, to reduce the thickness of the sheet. In order to control the temperature of the sheet, a temperature control tunnel 26 is provided immediately ahead of the rolls 24, 25, to have the sheet 21 pass therethrough. Depending upon the temperature of the sheet 21 as it leaves the drum 15, the interior of the tunnel 26 may be either heated or cooled as may be required to control the temperature of the zinc in passing through the rolls. This condition in the tunnel 26 may be produced by introducing either gas or oil through the pipe 27 to burn inside the tunnel or air or water to cool the zinc by flowing thereagainst.

Successive passing through reducing rollers is provided by carrying the sheet 21 continuously through as many consecutive rolls as may be desired to produce the final thickness of the sheet. As indicated by the drawing, a second tunnel 28 is provided immediately ahead of a second set of rolls 29, 30. In any event there should be a temperature control means at each set of rolls. As may be readily appreciated by those versed in the art, the working temperature range of zinc is 50 narrow and must be controlled very effectively to produce an acceptable sheet. When the molten zinc 10 is first poured into the hopper 19, it may be necessary to heat that hopper to prevent solidifying of the zinc therein until the hopper has

been brought up to a temperature sufficiently high to prevent solidifying, by continuous flow of the zinc therethrough as would be the case after the process has been once set in operation. This 5 heating of the hopper 19 may be produced by any suitable means such as by a gas jet flowing from a pipe 31 to have the flame play about the hopper.

From the foregoing description it will be apparent that a continuous formation of a finished 10 zinc strip is produced in a manner greatly reducing the cost of forming sheets and also in a manner which will form a sheet of any desirable length. It is to be understood, of course, that the initial cast sheet may be varied somewhat in 15 thickness by relative shifting of the plate 17 and the drum 15, one in respect to the other.

While I have described the invention above as referring to a sheet, I include within the meaning of "sheet" narrow strips or bars. That is, 20 the width of the sheet or strip is not limited but may be made any desired dimension and the cross sectional area may likewise be varied. Where a plurality of strips are required, the outer face of the drum 15 may be provided with a number 25 of partitions 32, Fig. 3, so that these strips or bars are separately molded and carried between the form and shaping rolls thereafter.

While I have herein shown and described my invention in the form that is now best known to me, it is possible to employ variations without departing from the spirit of the invention and I therefore do not desire to be limited thereto be-

yond the limitations as may be imposed by the following claims.

I claim:

1. That method of forming zinc strips in continuous lengths, which consists of flowing molten zinc into an arcuate strip forming mold, pulling the solidified zinc from the bottom of the mold to induce molten zinc to follow into the mold thereafter, straightening the zinc strip as it leaves the mold into substantially straight line travel, conducting the zinc strip through horizontal molds removed from the arcuate forming mold and having a controlled temperature independent of the temperature of said arcuate mold and conformable with that of the metal crystalline structure of 15 the zinc to prevent severance of the strip.

2. That method of forming zinc strips in continuous lengths, which consists of flowing molten zinc into an arcuate strip forming mold, pulling the solidified zinc from the bottom of the mold to induce molten zinc to follow into the mold thereafter, straightening the zinc strip as it leaves the mold into substantially straight line travel, conducting the zinc strip through horizontal molds removed from the arcuate forming mold and having a controlled temperature independent of the temperature of said arcuate mold and conformable with that of the metal crystalline structure of 25 the zinc to prevent severance of the strip, said maintenance of temperature being obtained by passing the continuous strip through heat controlled tunnels adjacent said forming means.

CLINTON I. WASSON.
